UNITED STATES PATENT OFFICE.

ROBERT E. ANDREWS, OF MOUNT GILEAD, NORTH CAROLINA, AND GEORGE REID ANDREWS, OF NEW YORK, N. Y.

MOP-HOLDER.

1,110,981.

Specification of Letters Patent. Patented Sept. 15, 1914.

Application filed November 21, 1913. Serial No. 802,803.

To all whom it may concern:

Be it known that we, ROBERT E. ANDREWS and GEORGE R. ANDREWS, citizens of the United States, residing at Mount Gilead 5 and New York, in the counties of Montgomery and New York and States of North Carolina and New York, respectively, have invented new and useful Improvements in Mop-Holders, of which the following is a 10 specification.

The present invention has reference to mop holders, and it proposes, briefly, certain hereinafter-described improvements in or relating to the construction of the two 15 main elements or members of the holder, and the means or devices provided in connection with said members for clamping the mop in place therebetween, whereby the attachment of the mop to, and its removal 20 from the holder may be readily effected.

An embodiment of the invention is illustrated in the accompanying drawing, wherein:

Figure 1 is a perspective view; Fig. 2 is 25 an enlarged plan view; and Figs. 3 and 4 are longitudinal and transverse vertical sections, respectively, taken centrally through Fig. 2.

As shown in said drawing, the improved 30 holder consists, primarily, of inner and outer ring-like members 1 and 2 of approximately elliptical shape, made of metal or other suitable material and so constructed and arranged as to exercise a clamping action 35 between them upon the mop, when the latter has been fitted over the inner member and moved with the same into the outer member. This clamping action is preferably obtained by giving to the walls of said 40 members a slight inward inclination, so that they have a somewhat frusto-conical appearance, such construction enabling them to mutually exert a wedging or binding action upon the interposed portion of the mop. 45 The latter may be of any desired type or material, and is shown in Figs. 1 to 4, wherein it is indicated by the numeral 3, as in the form of a strip of cloth having a central longitudinal slot 4, the purpose of 50 which will be subsequently explained. It is passed over the inner member 1, and clamped in place when that member is drawn upwardly into the outer member 2. To effect the upward movement just referred to, there 55 is preferably employed a threaded bolt 5

which projects upwardly through the bore of a guide socket or sleeve 6 formed centrally of a transverse strap 7 that connects the upper portions of the side walls of the outer member 2, and is located midway between the ends thereof. The lower end of the bolt is pivotally mounted upon a cross-pin 8 carried by a socket 9 that is located directly beneath the socket 6 and constitutes part of a strap 10 which joins the central portions of the side walls of the inner member 1 and is similar, in the main, to the upper strap 7, but of less height than that strap. The projecting upper portion of the bolt carries a clamping nut 11, the wings of which are elongated, as shown, and terminates in an enlargement or head 12 that serves to prevent removal of said nut, the bolt itself being preferably rectangular in cross-section and having its threads formed by notches 75 or the like in its longitudinal edges. As the lower end of the said bolt is mounted in the lower socket 9, an opening must be provided in the mop for the passage of the bolt therethrough; hence, the formation of the slot 4 80 in the mop when the latter is constituted by a strip of cloth, as shown. It is to be understood, however, that any other preferred form or type of mop may be employed in place thereof, according to the nature of the 85 work or the character of the surface to be swept or polished.

To facilitate manipulation of the device as a whole, the outer member 2 is provided with a suitable socket 25, to receive the lower 90 end of the pole or other handle 26.

The holder may be used with practically any desired form or type of mop, the latter being firmly clamped in place between the inner and outer members 1 and 2 when the 95 nut 11 is tightened. Both of said members are braced by the extension of the straps 7 and 10 thereacross, and the integral connection of the same thereto, this construction increasing the durability of the holder as 100 well as cheapening its cost of manufacture. Finally, the pivotal connection of the bolt to the lower strap 10 permits a lateral play which enables the said bolt to accommodate 105 itself to any slight irregularity in the relative positions of the inner and outer members.

We claim:

1. In a mop holder, the combination of inner and outer members having comple- 110

mental clamping surfaces adapted to grip the mop between them; a pair of sockets connected to said members in superposed relation, the lower socket having a cross-
5 pin therein, a bolt passing through said sockets and pivoted at its lower end upon said pin, and a device movably mounted on said bolt and adapted to be tightened against the upper socket to force the inner holder
10 member into the outer holder member.

2. In a mop holder, the combination of inner and outer ring-like members provided with complementary clamping surfaces adapted to grip the mop between them, each
15 of said members having a strap extending centrally thereacross and formed with a central socket; a bolt passing through said sockets and pivoted in one of them; and a

device carried by said bolt and adapted to be tightened against the other socket to force the inner holder member into the outer holder member.

In testimony whereof we have hereunto set our hands in presence of two subscribing witnesses.
